URINALYSIS FILTER UNIT

George A. Mast and John F. Lang, Milwaukee, Wis., assignors to Spincraft, Inc., Milwaukee, Wis., a corporation of Wisconsin

Application August 28, 1957, Serial No. 47,525

Term of patent 14 years

(Cl. D16—2)

Fig. 1.

Fig. 2.

Figure 1 is a front view partly in perspective of a urinalysis filter unit embodying our new design; and

Figure 2 is a perspective view of the filter unit viewed from one side and the top.

The dominant features of our design reside in those portions thereof shown in full lines.

The rear of the unit is substantially plain, and the opposite side is essentially the same in appearance as the side shown.

We claim:

The ornamental design for a urinalysis filter unit, as shown and described.
